Des. 232,135

Patented July 23, 1974

232,135

CIGARETTE LIGHTER CASE

Paul H. Dodson, Roanoke, Va., assignor to Dodson Specialties Incorporated, Roanoke, Va.

Filed Aug. 6, 1971, Ser. No. 169,892

Term of patent 14 years

Int. Cl. D2—07

U.S. Cl. D2—400

FIG. 1 is a front elevational view of a cigarette lighter case with the flap in closed position, showing my new design;

FIG. 2 is a front elevational view thereof, with the flap in open position;

FIG. 3 is a rear view thereof;

FIG. 4 is a side view thereof, the opposite side being substantially the mirror image of the side illustrated in FIG. 4; and

FIG. 5 is a bottom view thereof.

I claim:

The ornamental design for a cigarette lighter case, as shown and described.
